FIG - 3

INVENTOR,
FRED B. PFEIFFER
BY

ATTYS-

UNITED STATES PATENT OFFICE

2,626,519

DRIER

Fred B. Pfeiffer, Akron, Ohio

Application June 3, 1947, Serial No. 752,028

2 Claims. (Cl. 68—242)

1

My invention relates to improvements in machinery for extracting water from washed clothes, as for example, but without limitation, a family wash.

An object of the present invention is to provide means for drying clothes of a family wash by confining the wet clothes in a substantially air tight compartment and then withdrawing the water and air from such compartment by vacuum means.

Another object of the present invention is to provide a thin flexible diaphragm of rubber, or other similar flexible material, placed in such position relative to the clothes to be dried that when the compartment which the clothes occupy is subjected to vacuum, the differential fluid pressure on opposite sides of said diaphragm will cause the diaphragm to press against and about the said clothes, thus physically squeezing the water out of the clothes.

A further object of the present invention is to promote the drying of the clothes by subjecting them to reduced atmospheric pressure while the water they contain is still hot.

Yet another object of the present invention is to provide a clothes drier that will not injure buttons or delicate fabrics.

A still further object of the present invention, is to provide means for drying the clothes of a family wash which means does not involve the usual clothes wringers and to protect housewives from the dangers attendant to operating roll type wringers.

Another object of the invention is to provide convenient, economical means for drying a family wash which is faster than by the use of conventional roller type wringers.

Another object of the invention is to provide a drier for a family wash which may be operated by means of a motor driven pump or by a manually operated pump if electricity for a motor is not available.

Other advantages and objects will be apparent to those skilled in the art, from the description in the specification and by reference to the drawings, wherein:

Fig. 1 is a sectional view of a drier embodying the present invention, and showing the drier as it would appear when charged with wet clothes to be dried, and with its flexible diaphragm in position;

Fig. 2 is substantially the same as Fig. 1 but illustrating the relative positions of the clothes and diaphragm shown in Fig. 1 as they would appear after the drying operation and before the diaphragm has been removed; and

2

Fig. 3 is a top plan view of the drier with the diaphragm and clothes removed and a portion of the screen broken away.

Referring now to the drawings in detail and to Fig. 1 in particular it will be seen that a drier embodying the present invention and referred to in general as 10, comprises a body portion 11 supported on legs 12, a diaphragm cover 13, a loose screen 14 in the bottom of the main body portion, a pump referred to generally as 15, an adjustable pump handle 16, an outlet pipe 17, discharge hose 18, and other members identified hereinafter. Screen 14 has a raised dome-like central portion as shown in the drawing whereby the clothes being dried are prevented from bunching in the center of said body portion.

The body portion shown in Fig. 1 is round in the fashion of a round dish pan and has turned-over edges 19 for strength and to receive a beaded edge 20 of the diaphragm 13. The center of the bottom of the body 11 is in the form of a sump or a water collecting cavity 22. The side walls 9 of the sump 22 are annular having a reduced or neck portion 23 at the top portion thereof. This neck portion is adapted to receive a beaded edge portion of a diaphragm 24 of pump 15. It is to be noted that the bottom portion 25 of the body 11 slopes to the sump 22. While the body 11 is shown as having the general form of a round dish pan, it is to be understood that the invention is not to be limited to such shape, as obviously various shapes of compartments could be used.

At the top of the neck 23 a ledge portion 26 is formed to provide a seat for a perforated plate 27. This plate has a sufficient number of perforations 28 to permit water to flow freely into the sump 22. It is to be understood that the said dome portion of screen 14 will support the clothes independent of plate 27.

The bottom wall 35 of sump 22 is flat and through its central portion is a plurality of perforations 29 and a central bolt hole 30 to receive a bolt 31 having a head 32 and a threaded end on which is a nut 33. A molded circular rubber flap 34 is provided having a flat side facing the flat bottom 35 of the sump 22, and a convex surface facing downwardly from said bottom 35. The bolt extends through the bottom 35 and through a central hole, not shown, in flap 34, with the bolt head 32 resting on the upper surface of bottom 35 and the nut 33 tightened on the said flap, whereby the flat surface of said flap is normally held against the under side of bottom 35 and over perforations 29, thus forming a pump valve as will later be explained.

The diaphragm 24 is composed of thin rubber,

or other thin flexible material and is funnel shape. By reference to Fig. 1 it will be seen that this diaphragm 24 is tapered, the edges of the large end terminating in a bead 36 and near the edge of the small end is formed bead 37. The large bead 36 fits snugly in the neck 23 and is clamped therein by a hose clamp 38.

Pivotedly mounted on one of the legs 12 by means of a pivot pin 39 extending from said leg, a collar 40, and a set screw 41 is the outlet pipe 17 combined with the handle 16. The pump handle end portion of pipe 17 has an upwardly and downwardly turned portion 42 and 43 respectively with aligned holes therethrough. The top of portion 42 is closed except for a relatively small hole 44 over which hole a ball 45 is held by a spring 46 seated on a plug 47 threaded in the bottom portion 43 of said pipe 17, thus forming a ball check valve assembly. The upper end of portion 42 is formed with an annular groove 48 which receive the bead 37 of diaphragm 24. A hose clamp 49 clamps said bead 37 in fluid tight relation with said portion 42. A discharge hose 18 is attached to the outlet end of pipe 17 in any satisfactory manner as by a conventional hose connection 51.

The diaphragms 13 and 24 may be made in any manner found satisfactory as by molding on a core or by molding in a mold with internal fluid pressure, or from sheeted rubber or the like. The bead portions may be made separately from the wall of the diaphragm and cemented, or vulcanized to the walls, or by other expedients which may occur to those familiar with the art. The wall of the diaphragm 13 is preferably of thin rubber such as dental dam, while the wall of diaphragm 24 is of high grade rubber of substantial thickness since it is subjected to repeated flexing and must resist some pressure.

After washing, the wet clothes, referred to as 52, are transferred directly from the washing machine into the drier body 11. Next the elastic bead 20 composed of rubber which is of less length than the circumference of said body is snapped over the turned edges 19 of the body 11. The water and air is now removed from the clothes by the pump 15. The pumping action is performed by the operator grasping handle 16 and sliding it outwardly on a center rod 53 on which it is slidably mounted, the out position being shown in broken lines in Fig. 1. The handle is pumped up and down (see Fig. 2). At the beginning the excess water from the wet clothes will run down through the screen 14 over the bottom 25, through the perforations 28 of the plate 27 into the sump 22. It is to be noted that the screen 14 permits the water to flow along the bottom 35 and prevents the clothes from blocking such flow. The first upward stroke of handle 16 expels the air from diaphragm 24 the ball 45 being forced away from its seat by the force of the air being compressed by said upward stroke. Next the downward stroke of handle 16 tends to create a vacuum in diaphragm 24 which draws the edge portion of rubber flap 34 away from its seat against the bottom side of wall 35 thus exposing perforations 29 and drawing water out of the sump 22 (see Fig. 2). Next the handle is again raised which permits the return of and forces the flap 34 again against its seat on wall 35 and expels the water which has passed from sump 22 into diaphragm 24 out through hole 44 into outlet pipe 17 and hose 18. As will be understood by those familiar with the art as the pumping action continues both water and air will be

drawn out of the body 11. It being understood of course that the diaphragm 13 does not permit air to pass therethrough and that its beads are in fluid tight relation with the sides of the body 11. As the water becomes exhausted from the body 11 a partial vacuum is created therein and the hot water in the clothes boils and passes out to some extent as vapor. At any rate the differential of fluid pressure on the upper and lower side of the diaphragm 13 presses the thin rubber thereof tightly down against and around the wet clothes further squeezing all excess water therefrom.

It has been found that only a few strokes of handle 16 is necessary to dry clothes sufficiently for them to be hung upon a clothes line without dripping water. After drying the clothes, diaphragm 13 is removed and the clothes taken out of the drier and hung upon a clothes line, or otherwise handled according to the operator's desire.

While the present invention has been illustrated in connection with but one embodiment thereof, it is obvious that modifications will occur to those skilled in the art without departing from the spirit of the invention. The invention therefore is to be limited only by the scope of the appended claims and the prior art.

What is claimed is:

1. A clothes drier comprising a body portion adapted to receive wet clothes to be dried, a flexible diaphragm impervious to air or steam, the upper marginal edges of said body portion having continuous turned-over edges, said diaphragm terminating at its edge portion in an elastic bead composed of rubber which bead is of shorter length than the length of said turned-over edge, said bead being adapted to snap over said turned-edge thereby providing a fluid tight cover over said body portion, a drainage sump formed in the bottom of said body portion and the bottom of said body portion sloping toward said sump, a screen overlying said bottom, said screen having a raised dome shape center portion, a perforated plate concave on its upper surface covering the opening into said sump, said sump having a reduced neck portion adjacent its upper portion and at least one outlet hole through its bottom portion, supporting means for said body portion, an outlet pipe pivotally mounted on said supporting means, said pipe extending under said body and having a communicating check valve mounted on its inner end portion, a flexible pump diaphragm of frusto-conical shape when extended and extending between and connecting said sump and said check valve, said pump diaphragm being in fluid tight attachment to said sump and check valve, said outlet pipe having an extended portion on its end opposite its pivotal attachment, a pump handle slidably attached to said outlet pipe on said extended portion, and a flap attached to the underside of the bottom of said sump and with said bottom forming a check valve, said last mentioned check valve being of such size and so located that when closed it covers said opening through the bottom of said sump whereby water and vapor may be pumped from said body portion.

2. A clothes drier comprising a body portion adapted to receive wet clothes to be dried, a flexible diaphragm impervious to air or steam, said diaphragm terminating at its edge portion in an elastic bead which bead is of shorter length than the length of the upper marginal edge of said

body portion, said bead being adapted to snap over said marginal edge thereby providing a fluid tight cover over said body portion, a drain sump formed in the bottom of said body portion, said bottom having an opening therethrough communicating with said sump, a screen having a raised convexed center portion overlying said plate, said sump having a reduced neck portion at its upper end and a valved opening at its lower end, a flexible pump diaphragm of tubular shape when extended and having one end in fluid tight engagement with said neck portion, and a tubular means pivoted to the bottom of said body portion and secured to the other end of said pump diaphragm to operate said pump diaphragm to pump water and vapor from the body portion to said drain sump whereby water and vapor may be pumped from said body portion.
